Fig. 5

Fig. 7

Fig. 6

Fig. 1 is a top plan view of a canister or similar article, embodying my new design;

Fig. 2 is a front elevational view of the canister or similar article;

Fig. 3 is a side elevational view of the canister or similar article, as viewed from the right side of Fig. 2;

Fig. 4 is a fragmentary cross-sectional view, taken on the line 4-4 of Fig. 1;

Fig. 5 is a fragmentary cross-sectional view, taken on the line 5-5 of Fig. 1;

Fig. 6 is a fragmentary cross-sectional view, taken on the line 6-6 of Fig. 2, and

Fig. 7 is a fragmentary cross-sectional view, taken on the line 7-7 of Fig. 2.

I claim:

The ornamental design for a canister or similar article, substantially as shown.
